(57) **CLAIM**

The ornamental design for table frame of lifting table, as shown and described.

DESCRIPTION

Fig. 1.1 is a front elevational view thereof;

Fig. 1.2 is a bottom plan view thereof;

Fig. 1.3 is a rear elevational view thereof;

Fig. 1.4 is a right-side elevational view thereof;

Fig. 1.5 is a left-side elevational view thereof;

Fig. 1.6 is a first perspective view thereof;

Fig. 1.7 is a second perspective view thereof; and

Fig. 1.8 is a top plan view thereof.

The broken lines represent portions of the table frame of lifting table and form no part of the claimed design.

1 Claim, 8 Drawing Sheets
